UNITED STATES PATENT OFFICE

95,070

DESIGN FOR A PLAYING CARD

Joseph F. Rivard, Grosse Pointe Park, Mich.

Application January 5, 1934, Serial No. 50,320

Term of patent 3½ years

To all whom it may concern:

Be it known that I, Joseph F. Rivard, a citizen of the United States, residing at Grosse Pointe Park, in the county of Wayne and State of Michigan, have invented a new, original, and ornamental Design for Playing Cards, of which the following is a specification, reference being had to the accompanying drawing, forming a part thereof, in which is shown in plan view the back of a playing card embodying my design.

I claim:

The ornamental design for a playing card as shown.

JOSEPH F. RIVARD.
